ARTICLE OF PRINTER'S FURNITURE

Elmer L. Kokanour, Fort Lauderdale, Fla.

Application March 22, 1934, Serial No. 716,775

4 Claims. (Cl. 164—98)

The present invention relates to an article of printer's furniture which may be installed, one or more, on a part of a printing press that carries the impression sheet, for example such as the 5 platen of a job printing press, to simultaneously print and punch, or to enable the use of such a press as a punching machine, which may readily be accomplished, simply by omitting the printing form or type and operating the press in the usual 10 manner.

Oftentimes job printing shops or small printing shops are required to turn out punched work. Many of such shops are not equipped with punching machinery, hence have to effect the punching 15 operations in tedious and expensive manners. Then, too, such shops often have orders for loose-leaf work, requiring printing and punching of many sheets of paper. Such shops not properly equipped for punching are at disadvantages in 20 turning out such work, thus adding to the cost of production of such class of printed and punched matter.

The present invention has to do with a simple 25 punch device which may be readily attached, one or more, to a part of a printing press which carries the impression sheet, such for instance as the platen of a job press, to punch the impression sheet simultaneously with the printing operation.

30 An object of the present invention is to provide a punch device which may be readily applied to any part of a platen of a printing press for punching sheets of paper simultaneously with the printing impressions.

35 Another object of the invention is to provide a punch device readily applicable to a platen of a platen type press, by slitting the tympan draw sheet to receive the toe of the device and having a part to be clamped against the platen by the 40 bail.

A further object of the invention is to provide 45 an article of printer's furniture applicable to the part of a printing press which carries the impression sheet, whereby the sheet may be punched simultaneously with the printing impression or whereby the press may be operated as a punching machine.

Generally speaking the invention contemplates 50 a punch device which may be readily applied to any part of a platen, for punching holes in the impression sheet at desired places in such sheet. The invention contemplates such a device which punches the holes as the platen is moved against the printing form in the operation of the press.

55 The above, other and further objects of the

invention will be readily understood from the following description, accompanying drawing, and appended claims.

The accompanying drawing illustrates various forms of punch devices all embodying principles 5 of the present invention, and the views thereof are as follows:

Figure 1 is an isometric view of a platen type press, showing two punches, embodying the principles of the present invention, as applied to 10 the platen.

Figure 2 is a vertical longitudinal section through one form of the punch device.

Figure 3 is a top plan view of another form of punch device. 15

Figure 4 is a sectional view taken substantially in the plane of the line IV—IV of Figure 3 showing the punch as applied to a tympan.

Figure 5 is a fragmental plan view of a portion 20 of a platen, bail, and a punch device of the present invention.

Figure 6 is a front elevational view of the punch device of Figure 5.

Figure 7 is a top plan view of a punch device 25 of slightly different form.

Figure 8 is a sectional view taken substantially in the plane of line VIII—VIII of Figure 5, and showing the punch device in open position ready to receive an impression sheet.

Figure 9 is a view similar to that of Figure 8 30 showing the punch in closed or punching position, and

Figure 10 is a longitudinal vertical sectional view through another form of punch device.

The drawing will now be explained. 35

The press A is provided with a platen B and a bed C, the latter for supporting the usual type form in this class of press.

As is customary, a tympan draw sheet 1 is secured to the platen B by means of a bail 2 40 which is pivoted to the platen in the usual manner.

In the main, the punch device of the present invention, includes a structure having a plurality of leaves, preferably three, the lowermost of which 45 is herein termed the base leaf, the uppermost of which is termed the cutter leaf, and the intermediate leaf is termed the stripper leaf.

The punch illustrated in Figure 10 has a base leaf 3 with a downwardly turned heel 4 at its 50 rear end, for engaging between the platen B and the bail 2 for positioning this form of punch device on the platen. The cutter leaf 5 is of spring metal and it, together with the intermediate or stripper leaf 6 is secured to the base 55

leaf 3, adjacent the rear end thereof, in any suitable manner, such for instance as by spot-welding, as indicated at 7 in Figure 7. The base leaf 3 carries a cutter head 8 of any suitable form, the 5 form herein shown being cylindrical. The stripper leaf 6 is provided with an opening 9, larger than the diameter of the cutter head 8, so that the stripper leaf may be readily flexed in use. The cutter leaf 5 is provided with an opening 10 which 10 conforms to the shape and size of the cutter head 8 for cooperating therewith for punching purposes. The intermediate or stripper leaf 6 is preferably bowed so that normally a portion thereof lies even with or slightly above the cutter 15 head 8 to enable ready insertion of an impression sheet in the punch device. Furthermore the bowing of the stripper leaf enables flexing thereof during the punching operation as the flattening of the stripper leaf during the punching operation 20 enables it to spring back to normal position after the punching operation, and thus strip or free the sheet from about the cutter head, so that the sheet may be readily withdrawn.

The punch device illustrated in Figures 5 and 6, 25 is constructed quite similarly to that just described, except that the cutter leaf 11 has portions of its side eliminated, for increasing the spring effect of the cutter leaf during punching operations. Also, the base leaf is provided with lateral 30 lugs 12 which may be bent about adjacent portions of the cutter and stripper leaves at the rear end of the device, for an aid in holding together the leaves, in addition to spot welding.

The punch devices just described, that is those 35 illustrated in Figures 5, 6, 7, 8, 9 and 10, are applied to the platen B of the press, by inserting the heel or downturned flange 4 between the platen B and the bail 2, as illustrated in Figures 8 and 9, that is positioning the punch devices 40 adjacent the lower margin of the platen.

One, or several, of such devices may be readily applied to the platen as the punching job requires.

Sometimes it so happens that the impression sheet or other sheet must be punched in other 45 positions than readily accessible by the punch devices secured by the bail to the platen. In order to provide such punch devices, the forms illustrated in Figures 2, 3 and 4 are convenient.

The punch device of Figure 2 includes a base 50 leaf 13, a stripper leaf 14 and a cutter leaf 15. The base leaf 13 carries the cutter head 16 while the stripper leaf is provided with a suitable aperture to surround this cutter head, and the cutter leaf 15 is provided with an aperture 17 to cooperate with the cutter head, as heretofore described. The leaves are secured together adjacent the rear end thereof as by spot welding. For attachment of this form of punch device to the platen, or to the tympan, 18, the base leaf 13 55 may be extended to receive a bolt 19 having a flat head 20 which may be positioned underneath the tympan drawsheet 18, bearing against the underside thereof, with the bolt passing through a suitable hole in the draw sheet and through an aperture in the base leaf 13 of the device. A nut 21 is provided to clamp the punch device to the drawsheet in desired position. The base leaf 13 is furthermore provided with tangs 22 which are pointed and enter the draw sheet 18 to position the toe end of the punch device and retain it in fixed position during punching.

The punch device illustrated in Figures 3 and 4 is quite similar to that described with reference to Figure 2 in that it has a base leaf 23, a stripper leaf 24 and a cutter leaf 25, cutter head 26 with

a cutter leaf apertured at 27 to cooperate with the cutter head 26. These leaves are secured together at their rear ends as by spot welding. Adjacent the rear end of the base leaf 23, pins 28 are secured for entering the tympan drawsheet 18 for positioning the rear end of the punch device, while adjacent the toe end of the device are tangs 29 for entering the drawsheet to position the toe end of the punch device. 5

It will be observed that the punch device of Figures 3 and 4 may be readily applied anywhere on the surface of the platen simply by inserting the pins through the drawsheet and forcing the tangs 29 into the drawsheet.

The several leaves of the punch devices are 15 preferably of spring metal with the stripper leaf bowed and with the cutter leaf bent so that its free end may lie normally away from the cutter head of the punch device, to allow insertion of an impression sheet and also after the punching 20 operation to spring away from the cutter head for withdrawal of the punched sheet.

As an aid in the operation of the punch device, impression pads may be applied to the cutter leaf.

Figure 7 illustrates a pad 30 of U-shape in plan, 25 which is of rubber or other elastic material. This pad is applied to the outer surface of the cutter leaf 5 surrounding the aperture 10 therein, with the legs directed towards the rear end of the device, to guide the punchings toward the lower 30 end of the platen whereby these may fall from the platen after punching operations.

The form of impression pad illustrated in Figures 5, 6, 8 and 9 consists of two separated pads 31 and 32 of rubber or other suitable elastic material, retained on the cutter leaf by means of clips 33 securely fastened to such leaf. The disposition of the two pads 31 and 32 enables the use 35 of these as guides to prevent lateral disposition of the punchings as the platen is swung from impression position to open position for receiving another impression sheet. 40

In applying any of the punch devices of Figures 5, 6, 7, 8, 9 and 10, preferably the tympan drawsheet 18 is slotted, as at 34, to receive the toe of 45 the device and thus enable ready insertion of a sheet to be punched, and for positioning the device on the platen.

The invention has been described herein more or less precisely as to details, yet it is to be understood that the invention is not limited thereby, as changes may be made in the arrangement and proportion of parts, and equivalents may be substituted, without departing from the spirit and scope of the invention. 50

The invention is claimed as follows:

1. In combination with a printing press having a platen with a tympan bail, of a punch device applicable to said platen, said device having a part adapted to rest flatwise against the tympan drawsheet and a downturned heel for clamping between the platen and bail, said device having a toe portion adapted to enter a slit in said drawsheet, a cutter head, and a spring cutter leaf movable against said head as said platen is swung against the printing form, said cutter leaf springing away from said head when the platen is swung away from the printing form, stripper means carried by the said device for freeing the punched sheet from said cutter head, and a compressible pressure pad on said cutter leaf, said pad serving as a guide for directing the punchings away from the device. 60

2. An article of printer's furniture consisting of a punch device applicable to an appropriate 65

printing press for punching holes in an inserted sheet simultaneously with the printing operation; said device comprising a base leaf, a cutter leaf, and an intermediate stripper leaf; a cutter head 5 on said base leaf; said stripper leaf having an aperture in it to receive the cutter head during punching operation; said cutter leaf having an aperture to receive the cutter head for cooperating therewith to effect punching; said leaves being 10 connected together at one end with the other end of the cutter leaf normally spaced from the other ends of said base and stripper leaves; and said base leaf having one end downturned providing a flange for clamping between the platen and bail 15 and its other end constituting a toe portion adapted to enter a slit in the drawsheet, and a pressure pad of resilient material on said cutter leaf for engagement by a part of the press for forcing the cutter leaf against the cutter head for punching 20 purposes, and having portions along the cutter leaf serving as guide means for directing the punchings away from the device.

3. An article of manufacture comprising a

punch device adapted to be applied to the platen of a job printing press, said device having a heel for clamping engagement between the platen and bail of said press and having a toe adapted to enter a slit in the tympan drawsheet for positioning said device on the platen. 5

4. A punch device of the character described, comprising a plurality of separate flat plates of spring steel fastened together at one end and with the other ends vertically spaced one from another, 10 the lowermost of said plates carrying an upstanding punch or cutter element, the other plates being apertured for entry of said punch element in use, said device adapted to receive material between the top plate and the one immediately 15 below it, said last mentioned plate serving as a stripper to remove material from the punch element after a punching operation, and the lowermost plate having a downturned flange adapted to be clamped between the platen and bail to 20 secure said device in position on a printing press platen.
